CLAIM

The ornamental design for a hallux corrector, as shown and described.

DESCRIPTION

FIG. 1 is a perspective view of a hallux corrector showing our new design;

FIG. 2 is a front view thereof;

FIG. 3 is a rear view thereof;

(Continued)

FIG. 4 is a left side view thereof;
FIG. 5 is a right side view thereof;
FIG. 6 is a top view thereof;
FIG. 7 is a bottom view thereof; and,
FIG. 8 is a top view showing the hallux corrector in a state
of use.
Broken lines in the drawings depict portions of the hallux
corrector that form no part of the claimed design.
